APPLIANCE FOR MACHINE TAPPING OR SCREWING OPERATIONS

Harry Jones Andrew, Oldham, England

Application January 12, 1944, Serial No. 518,015
In Great Britain February 10, 1943

4 Claims. (Cl. 74—306)

This invention relates to appliances for the machine tapping or screwing of articles, such appliances being of the type in which the drive to the tool incorporates means for periodically reversing the drive so as to break up the metal removed during the tapping operation and therefore obviate damage thereby to the threads being produced or breakage of taps. Examples of such appliances are described and claimed in the specifications of my Patents Nos. 2,296,892 and 2,312,376 and of my co-pending application Serial No. 456,075.

The objects of the present invention are to reduce the diameter of the case containing the mechanism, to give a better balance to the mechanism, and when required to provide means whereby a large diameter sliding terminal shaft may be employed where it is desired to incorporate the device in the head of the present type of tapping machine.

The invention comprises, in combination, a revolving driving frame, two spindles secured in said frame parallel with its axis, a wheel upon one of said spindles driven from a fixed sun wheel co-axial with the frame, a wheel upon one of said spindles driving a shaft co-axial with the frame, and means on said spindles for imparting a back and forth movement which is progressively advancing in one direction from one of said wheels to the other.

The invention further comprises, in combination, a fixed case, a driving shaft journalled in said case, a sun wheel disposed around said driving shaft and fixed to the case, a driven shaft journalled in said case co-axial with the driving shaft and at the opposite side of the case to the latter, and a gear train comprising duplex wheels on each of the spindles in the frame for driving the driven shaft from said sun wheel, some of said wheels being of elliptical form.

The invention further comprises, in combination, a fixed case, a driving shaft journalled in said case, a sun wheel disposed around said driving shaft and fixed to the case, a driven shaft journalled in said case co-axial with the driving shaft and at the opposite side of the case to the latter, a planetary wheel upon one spindle driven by the fixed sun wheel as the frame revolves, a planetary wheel upon the other spindle driving the driven shaft, and cranks and connecting rods imparting back and forth movements to the latter planetary wheel from the former planetary wheel.

Referring to the accompanying explanatory drawings:

Figure 1 is a sectional elevation and Figure 2 a sectional plan on the line 2—2 of Figure 1 illustrating one form of my improved drive to a tapping tool.

Figure 3 is a view similar to Figure 1 but showing cranks and a connecting rod in place of elliptical wheels for giving the desired back and forth movement to the tapping tool.

Figure 4 is a sectional elevation on the line 4—4 of Figure 5, Figure 5 a sectional plan view on the line 5—5 of Figure 4 and Figure 6 a sectional elevation on the line 6—6 of Figure 5 illustrating a modified form of the improved drive.

Figure 7 is a view similar to Figure 5 but showing the use of cranks and a connecting rod in place of elliptical gears in the construction shown in Figures 4, 5 and 6.

In Figures 1 and 2, the case *a* is stationary and the shaft *b* is journalled in the top of the case 20 and is power driven. The bracket *c* may be used to clamp the case to any fixture. Secured upon a fixed sleeve *d* around the shaft *b* is a gear wheel *d*¹. The shaft *b* revolves a frame comprising an upper member *e* and a lower member *f* 25 interconnected by pillars *g*. Between the said upper and lower members extend two fixed spindles *h* and *i* with bearing sleeves *j* and *k* respectively thereon, upon which revolve gear wheels to be now described. A short shaft *m* is journalled in the upper member *e* and carries at one 30 end a wheel *n* meshing with the fixed gear wheel *d*¹ and at the other end a wheel *o* meshing with the wheel *p* which forms part of a duplex wheel *p*, *q* revolving freely on the sleeve *k* on the spindle *i*. The wheel *q* is an elliptical gear wheel 35 which meshes with a similar elliptical gear wheel *r* which also forms part of a duplex wheel *r*, *s* revolving about the sleeve *j* on the spindle *h*. The wheel *s* is an elliptical wheel and it meshes with a similar elliptical wheel *t* which forms part of a duplex wheel *t*, *u* revolving on the sleeve *k* on the spindle *i*. The wheel *u* is an elliptical wheel 40 and it meshes with the elliptical wheel *v* which is part of a duplex wheel *v*, *w* revolving on the sleeve *j* on the spindle *h*. The wheel *w* is a concentric wheel and it gears with a similar wheel *x* on the shaft *y* to which is secured the chuck *z* which holds the tapping tool being driven by the gearing. As the shaft *b* rotates the frame *e* 45, the gear train mounted therein revolves the chuck *z* but gives to it a back and forth circular movement with a progression forward.

The construction shown in Figure 3 resembles that shown in Figures 1 and 2 except that two cranks *8* and *9* and a connecting rod *10* serve to

give the back and forth movements instead of the elliptical gear wheels of Figures 1 and 2. In Figure 3, the case 11 is fixed and the shaft 12 rotates the frame comprising the upper and lower members 13 and 14 interconnected by pillars. There are two shafts 15 and 16 extending between 15 and journalled in the frame members 13 and 14. The shaft 15 has the gear wheel 17 thereon which meshes with the fixed gear wheel 18. As the frame revolves, the rotation of the shaft 15 causes, through the crank 8 in the shaft 15, the connecting rod 10 and the crank 9 in the shaft 16, a back and forth circular and not a complete rotary motion to be imparted to the shaft 16 and to the gear wheel 19 thereon. The latter 20 wheel gears with the wheel 20 on the shaft 21 carrying the chuck 22. In order to give better balance, each shaft 15, 16 may have a two throw crank therein, the throws being 180° apart, the throws of the two shafts being coupled by the use 25 of two connecting rods.

In the construction shown in Figures 4, 5 and 6, the frame 23 which carries the two spindles 24 and 25 is directly driven by belt or the like, the frame in the example illustrated being in the form of a pulley. The gearing on the spindles is similar to that in Figure 1 but in the present case the central spindle 26 is the driven spindle being also axially movable and splined in the wheel 31. Around it at one end is a fixed sleeve 27 having gear teeth thereon which mesh with an idler wheel 28 (in order to give the correct final direction of rotation from the mechanism). The latter wheel meshes with the wheel 29 which forms part of a duplex wheel 29, 30, the wheel 30 being an elliptical wheel. The said duplex wheel revolves freely on the spindle 24. The drive from the wheel 30 to the wheel 31 on the central shaft 26 is by the duplex wheel 32, 33 (both elliptical wheels) on the spindle 25, the duplex wheel 34, 35 (both elliptical wheels) on the spindle 24, and the duplex wheel 36, 37 (36 only of which is elliptical) on the spindle 25. The drive from the shaft 26 which is a back and forth drive with a progressive movement in one direction is taken by pulley, gear wheel or the like fixed on the shaft; or by fitting a chuck, carrying the tapping or other tool directly on the shaft.

The arrangement shown in Figure 7, utilises the frame 38 as a driving pulley, the spindles 39 and 40 being directly mounted in the pulley as in the construction shown in Figures 4, 5 and 6

but the back and forth movement for driving a gear 41 wheel fixed on the central axially movable shaft 42 from a fixed gear wheel 43 is obtained by gear wheels 44 and 45 on the spindles 39 and 40 and cranks 46 and 47 coupled to the wheels 44 and 45, and a connecting rod 48 exactly as illustrated in Figure 3. The crank 46 makes complete rotary movements but the crank 47 makes back and forth movements only. The frame 38 may form part of a two cone clutch as used in normal tapping machines.

What I claim is:

1. A mechanism of the type specified for use in the machine tapping or screwing of articles, comprising in combination, a revolving driving frame, two spindles secured in said frame parallel with its axis, a wheel upon one of said spindles driven from a fixed sun wheel co-axial with the frame, a wheel upon one of said spindles driving a shaft co-axial with the frame, and means on said spindles for imparting a back and forth circular movement which is progressively advancing in one direction from one of said wheels to the other.

2. A mechanism as claimed in claim 1, further comprising in combination, a fixed case, a driving shaft journalled in said case, a sun wheel disposed around said driving shaft and fixed to the case, a driven shaft journalled in said case co-axial with the driving shaft and at the opposite side of the case to the latter, and a gear train comprising duplex wheels on each of the spindles in the form for driving the driven shaft from said sun wheel, some of said wheels being of elliptical form.

3. A mechanism as claimed in claim 1, further comprising, in combination, a fixed case, a driving shaft journalled in said case, a sun wheel disposed around said driving shaft and fixed to the case, a driven shaft journalled in said case co-axial with the driving shaft and at the opposite side of the case to the latter, a planetary wheel upon one spindle driven by the fixed sun wheel as the frame revolves, a planetary wheel upon the other spindle driving the driven shaft, and cranks and connecting rods imparting back and forth movements to the latter planetary wheel from the former planetary wheel.

4. In a mechanism as claimed in claim 1, the arrangement in which the frame revolves and constitutes a driven pulley or wheel.

HARRY JONES ANDREW.
